UNITED STATES PATENT OFFICE

2,074,775

LEAD-HEADED NAIL

Raymond E. Camp and John J. Strysik, Joliet,
Ill., assignors to The American Steel and Wire
Company of New Jersey, a corporation of New
Jersey

Application June 17, 1935, Serial No. 27,073

3 Claims. (Cl. 85—28)

This invention relates to lead-headed nails which broadly consist of steel wire nails providing integral heads to which lead is applied so as to enclose the same.

5 One of the objects is to improve such nails so as to eliminate slipping or loosening of the lead respecting their steel heads. Other objects may be inferred.

Referring to the accompanying drawing:

10 Figure 1 shows the side of a nail which illustrates the present invention and as it appears before its head is enclosed with lead.

Figure 2 shows the top of this nail.

15 Figure 3 shows the nail after its head is enclosed with lead, the head and lead part being sectioned.

The nail illustrated by the above drawing includes a shank 1 and a head 2 that is characterized by being rectangular whereby it provides 20 straight side edges. Figure 3 shows the nail as it

appears ready for use; its head 2 being enclosed by a relatively plastic substance, such as lead.

Now it is to be understood that the steel head within the lead of most lead-headed nails is of the familiar circular form. This permits a rotative movement between the lead and the steel head so that the former often becomes loosened from the latter. The straight side edges provided by the peculiar shape of the head 2 functions to lock the lead 3 against respective rotation 10 and possible consequent loosening. 5

We claim:

1. A nail including a shank and a substantially continuous and smooth-bottomed head overhanging said shank and providing at least one straight 15 side edge, said head being enclosed by lead.

2. A nail including a shank and a rectangular head overhanging said shank, said head being enclosed by lead.
